UNITED STATES PATENT OFFICE.

UTLEY WEDGE, OF ARDMORE, PENNSYLVANIA.

ELECTRICAL HEATING DEVICE FOR METALLURGICAL FURNACES.

1,088,496.

Specification of Letters Patent.

Patented Feb. 24, 1914.

Application filed June 19, 1912. Serial No. 704,525.

To all whom it may concern:

Be it known that I, UTLEY WEDGE, a citizen of the United States, residing in Ardmore, Pennsylvania, have invented certain 5 Improvements in Electrical Heating Devices for Metallurgical Furnaces, of which the following is a specification.

The object of my invention is to provide effective means for electrically heating the 10 working chambers of metallurgical furnaces. This object I attain in the manner hereinafter set forth, reference being had to the accompanying drawing, in which--

Figure 1 is a transverse vertical section 15 of an ordinary type of metallurgical furnace equipped with an electrical heating system in accordance with my invention; Fig. 2 is a horizontal section on the line *a—a*, Fig. 1, looking upwardly toward the roof of the 20 working chamber, and Fig. 3 is a view similar to Fig. 2, but on a smaller scale, and illustrating another system of wiring.

In the drawing, I have illustrated my invention as applied to that type of furnace 25 which has a plurality of superposed working chambers, 1 representing the outer wall of the furnace and 2 a series of horizontal partitions, each of which forms the hearth of the chamber above it and the arch or roof of the chamber below it, a furnace of this type being usually provided with a central rotating shaft 3 equipped in each working chamber with a series of rabble arms (not shown in the drawing), for feeding and stirring the material deposited upon the hearth of the chamber, the material under treatment flowing downwardly from chamber to chamber through suitable openings in the hearths. My invention is not, however, limited to a 40 furnace of this type.

My invention consists in disposing an electrical resistance body in the upper portion of the working chamber, so that when it is heated, by the passage of an electric 45 current, it will radiate this heat downwardly upon the material upon the hearth below. Preferably, the electrical resistance body employed is located close to the roof of the working chamber and is suspended therefrom by means which will resist the high degree of temperature usually maintained in the working chambers of this class of furnaces. Preferably, also, the electrical resistance body is disposed with some degree 50 of uniformity throughout the area of the working chamber so that the heat radiated

therefrom will be disseminated with a like degree of uniformity throughout the material lying upon the hearth of the chamber.

The resistance body employed must be one 60 which is not injuriously affected by the heat and gases of the furnace and I also prefer one in which the necessary strength and other desired qualities can be secured while still retaining a relatively small cross sectional area in the resistance body. After 65 long experiment I find that a suitable material for the resistance body is the metal or alloy known as Nichrome.

In that embodiment of my invention 70 shown in Figs. 1 and 2 the resistance bodies 4 consist of wires extending either straight across from one side of the furnace chamber to the other or looped in that portion of the furnace in which the central shaft prevents 75 them from being carried straight across from one side to the other, the opposite ends of these wires being connected to terminal plugs 5, preferably mounted in suitable non-conducting sleeves 6 in the walls of the furnace and respectively connected to the opposite 80 poles of the electric generator as indicated by the plus and minus signs in Fig. 2.

In order to properly support the wires 4 close to the roof or arch of each working 85 chamber, I prefer to employ loops 7 embedded in the brick work or other material of which the horizontal partitions 2 are composed, although other means of supporting the wires or other resistance bodies may 90 be adopted if desired, without departing from the essential feature of my invention. Instead of employing a series of independent resisting bodies, as shown in Fig. 2, I 95 may employ a single resistance body so disposed as to extend throughout the area of the working chamber, one instance of such disposal being shown in Fig. 3.

In some cases I propose to use in addition to the electrical resistance bodies on the 100 roof of the working chamber other electrical resistance bodies on the side walls of the chamber, and I may even mount them upon the refractory covering 8 of the central rotating shaft 3. In Fig. 1 I have shown such 105 resistance body 4^a on the side walls 1 of the chambers and a resistance body 4^b on the rotating shaft in another one of the chambers. The resistance body 4^a constitutes a single line extending from one terminal 5^a to the 110 other, although there may be as many lines as desired, and each line may completely

encircle the furnace or may extend only part way around the same, as desired, and instead of extending in straight lines the conductors may be waved, corrugated, or otherwise disposed, so as to increase their surface area. The conductors 4^b mounted upon the rotating shaft preferably communicate with contact rings 9 on the interior of the shaft which contact rings may receive the terminals of the stationary conductors located in the interior of the shaft.

I claim:

1. The combination of a metallurgical furnace having a working chamber therein, with an electrical resistance body contained in said working chamber and supported by loops embedded in the structural portion of the furnace adjacent to which the electrical resistance body is disposed, said loops projecting into the working chamber to receive the resistance body.
2. The combination of a metallurgical furnace having a central rotating shaft, with an electrical resistance body mounted upon said shaft and contained in a working chamber of the furnace.
3. The combination of a metallurgical furnace having a working chamber therein,

with an electrical resistance body contained in the upper portion of said working chamber so as to radiate heat downwardly upon the material on the hearth of the chamber, and means for suspending said electrical resistance body from the roof of the working chamber, said suspending means comprising loops embedded in the material of which said roof is composed, and projecting down into the working chamber to receive the resistance body.

4. The combination of a metallurgical furnace having a series of superposed working chambers and a central rotating rabble-carrying shaft, with electrical resistance bodies mounted in the upper portion of a plurality of said working chambers so as to radiate heat downwardly upon the material on the hearths of the chambers as said material is being agitated by the rabbles.

In testimony whereof I have signed my name to this specification, in the presence of two subscribing witnesses.

UTLEY WEDGE.
